UNITED STATES PATENT OFFICE

ANDREW CHRISTIANSON, OF PITTSBURGH, PENNSYLVANIA, ASSIGNOR TO STANDARD STEEL CAR CORPORATION, A CORPORATION OF PENNSYLVANIA

INTERNAL-COMBUSTION-ENGINE COOLING SYSTEM

Application filed September 22, 1927. Serial No. 221,266.

This invention relates to motor driven railroad cars and more particularly to cooling systems for the motors employed in operating such cars.

5 An object of this invention is to provide a cooling system of the type set forth having an improved construction and arrangement of parts and including novel features that render it particularly efficient and practical 10 and peculiarly adapted for use in railroad service.

This and other objects which will be apparent to those skilled in this particular art are accomplished by means of the invention 15 illustrated in the accompanying drawings, in which Figure 1 is a transverse sectional view through a railroad car provided with a cooling system constructed in accordance with one embodiment of this invention. Fig. 20 Fig. 2 is a similar view of a portion of the arrangement shown in Fig. 1. Fig. 3 is a view of a detail. Fig. 4 is a view similar to Fig. 2 of another portion of the apparatus as shown in Fig. 1. Fig. 5 is a longitudinal sectional 25 view on the line 5—5 of Fig. 1. Fig. 6 is a view similar to Fig. 1 showing a modified arrangement, and Figs. 7 and 8 are details of a valve used in the arrangement shown in Fig. 6.

30 The particular embodiment of this invention which has been chosen for the purposes of illustration includes a storage tank for holding a supply of cooling fluid. Any desired type of pump can be employed for forcing the fluid from the storage tank through the jackets of the motor cylinders. The hot fluid is carried upwardly to a collecting or mixing chamber above the motor and this chamber is connected by piping with headers extending longitudinally of the car beneath the edges of the roof. The cooling radiators are positioned outside of the car above the roof and valve control radiator inlet pipes connect the lower ends of the radiator units to the longitudinally extending headers. The fluid flows upwardly through the inclined radiator units to the ends adjacent the center of the car and then into headers which are connected by piping 45 extending downwardly through the roof to

a return or collecting header from which the fluid is returned by a suitable pipe back to the storage tank. A by-pass is provided for permitting the fluid to flow directly from the distributing or mixing chamber to the storage tank without passing through the radiators so as to permit rapid warming up of the motor in cold weather. The radiator supports are so arranged as to extend loosely through openings in the car roof to prevent the vibration of the car body reaching the radiator units. The system is so constructed and arranged as to be completely self draining, so that as soon as the engine stops the cooling fluid is drained by gravity from the radiators and headers into the storage tank. The latter is so positioned that when the motor is idle the level of the fluid therein is well above the highest jacket on the engine.

55 As illustrated, the invention is shown in connection with a motor driven railroad car 10 provided with a motor 11, only part of which is shown in Fig. 1. A storage tank 12 is connected to the water jackets (not shown) of the motor cylinders by suitable piping and a pump (not shown) of any desired form is provided for forcing the water from the motor cylinders through vertically extending pipes 13 to a relatively small distributing tank 14 positioned above the motor. The distributing chamber is connected by piping 15 to headers 16 extending longitudinally along each side of the car body beneath the edges of the car roof 17, and each header is secured in place by straps 18 bolted to upright extensions 19 of the car body. A plurality of separate radiator units are supported in inclined positions above and transversely to the car roof and the lower end of each unit has a header 20 connected in parallel or in shunt by piping 21 extending loosely through openings 22 in the car roof to headers 16. Each branch pipe 21 is provided with a manually operated valve 23 for opening and closing the associated radiator inlet and a hose connection 24 is provided for connecting each pipe 21 with the inlet 25 of the associated radiator unit. Mechanism such, for example, as a petticoat 26 mounted on the pipe 21 is pro- 60 65 70 75 80 85 90 95 100

vided for covering the opening in the roof through which the pipe extends so as to prevent the entrance of rain or the like to the interior of the car through the roof openings. The lower inlet end of each radiator unit is supported upon an S shaped radiator supporting bracket 27 having an opening through which a pin 28 secured to and extending downwardly from the radiator header is received, and a spiral spring 29 is interposed on the pin 28 between the bracket and the header so as to provide a cushion support for absorbing any vibrations of the bracket. As shown, the S bracket 27 is rigidly secured to the roof 17 of the car and has a hole or slot cut through the bent or face portion of its extending end. The spiral spring 29, as shown, preferably consists of two sections one interposed above the face portion of the bracket 27, the other interposed below the face portion thereof. The fluid transmitting radiator tubes 30, diagrammatically shown in Figs. 2 and 4, are inclined upwardly from a tube sheet 31 in the inlet header 20 to a tube sheet 32 in the radiator outlet header 33 which is connected by piping 34 with a return header 35 extending longitudinally along the center of the car and supported beneath the roof by supporting straps 36 bolted to the car lines 37. The radiator outlet headers 33 of each unit are connected in parallel with the return header 35 through the piping 34. The piping connecting the outlet headers of the various radiator units with the collecting or return header 35 extend through openings 38 in the car roof which are surrounded by upwardly extending flanges 39 cooperating with flanged plates or petticoats 40 bolted to the piping 34 so as to cover the openings 38 above the surrounding flanges 39 to prevent the entrance of rain or the like into the car.

The outlet header of each radiator unit is provided with a baffle 41, see Fig. 4, which is spaced from the tube ends and extends from the bottom of the header to a position adjacent the top thereof. Such a baffle insures the complete filling of each radiator unit and the flow of water through all the tubes thereof during operation of the system.

The return header 35 is connected with a return pipe 42 for conveying water therefrom back to the storage tank 12.

A by-pass 43 having a valve 44 is provided for permitting the water to flow directly from the distributing or mixing chamber 14 through the piping 15 and back to the storage tank 12 without passing through the various radiator units when it is desired to rapidly warm the motor in starting in cold weather, and this by-pass is conveniently operated by opening or closing the controlling valve 44.

In operation the water is taken from the

storage tank by the circulating pump and forced through the various water jackets of the motor from which it passes to the distributing or mixing chamber or tank 14. From the distributing tank the hot water flows to the longitudinally extending headers 16 communicating with the various radiator units positioned above the car roof. From the header the water flows upwardly through the various piping connections 21 to the associated radiator units where it is cooled and from which it returns through the pipes 34 to the return header 35 extending longitudinally of the car and connected to each of the radiator units. The cooled water is then returned to the storage tank through the return pipe 42. It will be apparent that any number of radiator units can be cut out of operation independently of any other units merely by closing the associated inlet valves 23. It will also be apparent that opening of the by-pass valve 44 permits the circulating water to bypass all of the radiator units and return directly to the storage tank from the distributing chamber 14 so as to permit rapid warming of the motor in cold weather.

One advantage of the present system is the fact that it is completely self-draining. The inclination of the radiator units and piping connections is obviously such, see Fig. 1, that when the motor is stopped and the valve 44 open the water will be drained by gravity from all the various radiator units and connecting pipes back to the storage tank 12. The latter is so arranged that when the system is not in operation, the level of the water is well above the highest water jacket on the engine.

Figs. 6 to 8 illustrate a modification of the present invention of such arrangement as to be capable of being employed in using either steam or water as a cooling agent, and the arrangement is such that the system can be adapted for one or the other of such cooling agents merely by the operation of a single valve. As illustrated, the water jackets of the engine are connected by piping 13' to a control valve 50 located within the mixing or distribution chamber 50' having a port 51 connected to the piping 13'. A second port 52 is connected by suitable piping 53 with the longitudinally extending header 16 at each side of the car. A third port 53 is connected by piping 55 to the storage tank 12 and a fourth port 56 is connected to the central header 35 by piping 57. Valve plug 58 having suitable passages 59 for cooperating with the various ports is provided with, and is operated by, any convenient means, such as a handle 60. If water is employed as the cooling agent, the valve plug 58 is positioned as shown in Fig. 7 and the operation is similar to the operation of the arrangement shown in Fig. 1. The heated water ascends through the piping 13' to the valve 50, through the

ports 51 and 52 and piping 53 to the header 16. The cool water collected in the header 35 flows through the piping 57, valve ports 53 and 56 and piping 55 to the storage tank.

When steam is employed, the valve plug 58 is positioned as shown in Fig. 8. The heated steam rises through the piping 13' and flows through ports 51 and 56 of the valve to piping 57, whence it reaches the radiators through the header 35 and associated radiator connections. The cooled steam runs outwardly through each radiator unit and collects in the longitudinal header 16 from whence it flows to the valve 50 through the piping 53 and passes through the valve ports 53 and 59 to the piping 55 and thence to the storage tank.

Although I have described specific embodiments of this invention in more or less detail, it will be apparent that various changes, additions, substitutions and omissions can be made therein without departing from the spirit of this invention or the scope of the appended claims.

25 What I claim as new and desire to secure by Letters Patent is:

1. The combination in a railroad motor car of a motor cooling system including a radiator positioned above the roof of said car, a water pipe extending loosely through an opening formed in said roof, means for resiliently supporting said radiator on said roof and a yielding water-conveying connection between said pipe and said radiator.

2. The combination in a railway motor car of a motor cooling system including a radiator positioned above the roof of said car, a radiator supporting bracket secured to said roof and a pin and spring connection between said bracket and said radiator.

3. The combination with a motor car having a cooling system that includes radiator units, of means rigidly secured to the body of the car cooperating with means extending from the radiator units, additional means interposed between the above mentioned means for resiliently supporting said radiator units on the body of the car.

4. The combination with a motor car having suitable radiator units, of means rigidly secured to the roof of said car and extending upwardly therefrom, means extending downwardly from said radiator units and cooperating with the first mentioned means, a spring positioned on the last mentioned means and interposed to absorb vibrations of the motor car.

5. The combination with a motor car cooling system which includes suitable radiator units, of an extending bracket secured to the body portion of the car, the extending end of said bracket having a slot cut therein for receiving a pin secured to and extending from the radiator units, a spring interposed on said pin between said bracket and the radiator

unit, so that said radiator unit will be cushioned with respect to the body of said car.

6. The combination with a motor car having suitable radiator units positioned on the roof thereof, of S shaped brackets extending from and rigidly secured to the car roof, each of said brackets having a slot cut in its upper face, pins secured to and extending from said radiator units, each pin being positioned in one of said slots, means interposed on each of said pins between each of said brackets providing a cushioned support for said units.

7. The combination with a motor car, of a plurality of radiator units positioned transversely on the roof of said car, S shaped brackets extending upwardly from said roof and cooperating with pins extending downwardly from said units, springs positioned on said pins and interposed between said brackets and said units providing a cushioning support for said units.

8. The combination in a motor driven car, of a cooling system therefor which includes a longitudinally extending centrally positioned header, longitudinally extending headers positioned on either side of said car, a plurality of radiator units transversely positioned above and inclining downwardly from the transverse center of the roof of said car and connected with said headers through suitable piping, said headers being connected through suitable piping to water jackets of the car and to a storage tank, valves interposed in said piping for directing the flow of warm water upward through said radiator units and outward to said storage tank, and for directing steam downward through said pipes and to said tank.

In testimony whereof, I have hereunto subscribed my name this 25th day of July, 1927.

ANDREW CHRISTIANSON.
